UNITED STATES PATENT OFFICE

HARRY E. HOWLAND, OF ITHACA, NEW YORK, ASSIGNOR TO ITHACA GUN COMPANY, OF ITHACA, NEW YORK, A CORPORATION OF NEW YORK

MECHANISM FOR FIREARMS

Application filed May 7, 1931. Serial No. 535,739.

The present invention relates to breech mechanisms for fire arms and more particularly to the so-called "pump gun" type or in other words a gun having a tubular magazine carried directly under the barrel and which is operated for loading, extracting and ejecting of the empty cartridge case of the reciprocation of a slide handle.

The entire breech mechanism is housed in a receiver which is closed on all sides but the bottom, through which the filling of the magazine and the ejection of the shell or empty cartridge case takes place.

The main parts of the breech mechanism are the breech block with the firing pin and extractor, the slide for reciprocating the breech block, the hammer, trigger, cartridge carrier and shell stop.

This invention forms a further development and improvement on the mechanism of the Browning Patent No. 1,143,170, many of the parts being identical.

Some of the aims and advantages of this invention will here be enumerated:

25 The breech block is practically solid with a whole top and only small cuts on the underside for the extractor and the slide. This requires very little and easy machining with consequent lessening of costs.

30 Another advantage is the position of the firing pin centrally in the breech block with its axis coinciding with the axis of the bore. This also facilitates machining and boring of the breech block. It also tends to give a more direct and therefore more effective blow of the firing pin for igniting the cap in the cartridge case as compared with the slanting and less effective blow of the firing pin in other guns.

40 With the diminishing of the cavities and cuts in the breech block and the substantially complete inclosure of the firing pin and its retracting spring, there will be practically no collection of dirt, grit and dust thus easy and free movement of parts is assured.

The extractor is quite small and stocky, well balanced and mounted to rock in a small recess provided on the under side of the breech block near the forward end thereof. It has no cuts or recesses and the coil spring, actuating it, engages the short tail-end thereof. As it is fulcrumed substantially in alignment with the bottom of the bore, it is very effective and has no tendency of slipping off the cartridge rim in extracting.

The ejection downwardly of the empty case or shell through the bottom of the carrier is, on account of the solidly built extractor, very powerful and sure. A feature not seen in other guns is the firm grip which the nose of the extractor has on the cartridge case rim after the slide has traveled rearward a short distance and at the moment when the slide engages the bottom lug of the breech block for releasing the same from the abutment shoulder in the top of the receiver. At this moment the extractor is lowered with the breech block and the underside of the forward end of the extractor comes in contact with the forward cam surface of the slide thus locking the extractor with the rim of the cartridge case.

To summarize, the following are the main objects and advantages of the present invention:

(a) A dust and dirt proof mounting of the firing pin in the breech block.

(b) A firing pin completely enclosed in the breech block.

(c) A firing pin adapted to deliver an axial, direct (not slanting) blow against the cartridge case.

(d) A breech block having a straight axial bore to house the firing pin.

(e) A breech block having solid top, sides and ends with only one central bore and small bottom cuts to accommodate the extractor and the slide lugs respectively.

(f) A solid, substantially balanced, extractor housed in the breech block in a small

recess at the forward end thereof on its under side.

(g) An extractor also serving as cartridge ejector to expel the cartridge through the bottom of the receiver.

(h) An extractor positively gripping the cartridge rim actuated by a cam surface on the slide at the moment when the latter engages the bottom lug of the breech block for releasing it from the shoulder in top of the receiver.

In the accompanying drawings one embodiment of the invention is illustrated, and

Figure 1 shows a vertical, longitudinal section of the receiver and breech mechanism with the parts in position immediately after firing;

Figure 2 is a view similar to Figure 1, but with the breech block partly retracted and all moving parts in elevation instead of section;

Figure 3 is a view similar to Figure 1, showing the breech block full retracted;

Figure 4 is a transverse section taken along line 4—4 of Figure 3;

Figure 5 is a plan view of the slide; and

Figure 6 is a side elevation of a detail in section.

Like reference characters refer to the same parts in the different views.

Some of the parts are similar or identical with those shown and described in Patent 1,143,170 of which this invention forms a further improvement and they are accordingly not claimed here. They are however necessary for cooperation with new and improved parts. Such known parts are the hammer and its main spring and intermediate parts, the trigger, trigger-guard, slide and slide stop or safety sear, carrier and cartridge strap, etc.

Reference numeral 25 indicates the receiver which is closed on all sides except the bottom 26. It has two flat side walls 27, 28 and an arched roof 29. At its forward end is secured the barrel 30 and beneath the same the tubular cartridge magazine 31 preferably by interrupted threads. The receiver is at its rear end secured in usual manner to the stock 32 which, together with the trigger guard 33 completely closes the rear end of the receiver. The trigger guard is secured between the side walls 27 and 28 and extends forward in the bottom opening 26 of the receiver 25 thereby closing it for about half its length. The trigger 34 is pivoted on the pin or spindle 35 in the trigger guard and engages with its forward extension 36 a notch 37 in the lower end of the hammer 38 when in cocked position as best seen in Figure 3. The trigger extension is urged upwardly into such engagement by the coiled spring 39. A safety pin 40 is shown in the trigger guard to the rear of the trigger 34 and is adapted to be

set to prevent the pulling of the trigger accidentally.

A slide stop 41 is also pivoted on the pin 35 and, actuated by a coiled spring 42, engages the rear end of the slide 43, when the mechanism is in firing position, thereby preventing the opening of the mechanism in case of hang-fire. The slide 43 is guided in grooves 44 cut in the sides 27 and 28 of the receiver and parallel to the gun axis thereby permitting straight reciprocation of the slide actuated by the loading handle (not shown) on the magazine through the intermediary of the operating rod or slide-bar 45. The latter is connected to the slide by means of a pin 46 secured therein.

Soon after starting on its rearward movement, the slide 43 with its recess 47 engages a corresponding lug 48 provided on the under side of the breech block 50.

Unlike former constructions, the breech block consists of a practically solid piece of metal with flat sides and an arched top surface. At its rear end is provided an upstanding lug or projection 51 which engages a corresponding recess 52 in the top of the receiver when the block is in its firing or forward position, see Figure 1. The rear face 53 is slanting backwards and constitutes an abutment shoulder for the breech block taking up the blow from the firing. In this position, the top face of the breech block is parallel with the bore of the barrel 30 and the axis of the firing pin 54, which is housed in the breech block, is in exact alignment with the axis of the gun bore. The firing pin is cylindrical throughout with a firing pin point 54 of small diameter and the rear end 55 of large diameter thus forming a shoulder 56 for the retracting spring 57 wound around the firing pin point 54 and abutting against the forward wall of the firing pin seat 58. The firing pin has a limited movement in its seat governed by a transverse pin 59 in the breech block, engaging a slot 60 in the rear heavy end 55 of the firing pin. Thus, when not driven forward by the hammer 38, to puncture the cartridge case cap, as seen in Figure 1, the rear end 55 of the firing pin projects a short distance beyond the straight rear face of the breech block, see Figures 2 and 3. The drilled hole running through the solid breech block forming the seat for the firing pin, constitutes a dust and dirt proof enclosure for the same. This is of great importance, because upon the easy and perfect working of the firing pin depends to a great extent the correct functioning of the entire firing mechanism.

On the underside of the breech block 50, near its forward end is pivoted on a small pin 63 the short extractor 64 almost at its middle so as to practically balance itself. A small recess 65 is milled out of the breech block forming a seat just large enough to permit a

slight oscillation of the extractor. Its nose 66 is formed as a hook for engaging the rim of the cartridge case and its tail 67 is engaged by a compression spring 68 lodged in a drilled hole in the breech block. Said spring thus tends to press the tail downwardly, thus swinging the nose 66 upwardly for engaging the cartridge case rim 69. Opposite the seat 65 is cut out another recess 70 to accommodate the extractor which projects slightly below the bottom of the breech block. The special function of this recess 70 will be described later.

Forward of the lug 48 to the seat 65, the bottom portion of the breech block 50 is cut away as at 73 in order to permit the rearwardly slanting cam surface 74 of the slide recess to engage the correspondingly inclined forward surface 75 of the lug 48 on the breech block during the rearward or opening movement thereof.

In its firing position, as seen in Figure 1, when the breech block engages with its projection 51 in the receiver recess 52, then the bottom face of its lug 48 rests on the rear end of the slide 43, while the cam surfaces 74 and 75 are separated. Directly the slide 43 begins to move rearwardly the cam surface 74 approaches the cam surface 75 of the lug 48 and after only a short travel, the said surfaces become engaged and after a further movement of the slide the lug 48 is compelled to travel downwards into the recess 47 of the slide. This causes the rear end of the breech block to tilt downwards until the projection 51 becomes disengaged from the receiver recess 53 and the breech block 50 is free to move rearwards with the slide 43.

With the breech block moves also the extractor 64 which with its nose 66 engages the rim 69 of the cartridge case after only a slight rearward movement of the breech block and actuated by the spring 68. The lowering of the breech block as regards the slide also causes the underside of the forward end of the extractor 64 to abut against the bottom of the forward recess 70 in the slide 43 in this manner creating a firm, unyielding grip, on the cartridge case 76. The latter is thus drawn out of the bore as indicated in Figure 2. How the carrier 77 pivoted at 78 in the receiver 25, is swung upwards from its middle position, seen in Fig. 1, to its uppermost position, seen in Figure 2, by the action of the breech block 50 during its retraction, forms no part of the present invention, but is fully described in the above named Browning patent. On the inside of the carrier arms are provided a pair of small abutments 79 engaging the upper portion of the cartridge rim 69 when the cartridge case has been still further retracted. As the cartridge case thus meets with an obstruction while the extractor tries to draw the case further back, the cartridge case will be swung downwards

with its open end first until it ultimately drops away from the extractor and falls through the bottom opening 26 of the receiver 25.

The rearmost position of the breech block and slide is shown in Figure 3 when the rounded rear end 80 of the slide 43 engages the tail 81 of the carrier 77 lifting the same thereby causing the forward arms of the carrier to descend, see Figure 3, in position to receive the next cartridge case from the magazine. The carrier and its operation form no part of the present invention, but is fully described in said Browning patent. Similarly the operation of the positive stop 82 pivoted at 83 in the receiver and other parts assisting in feeding a new cartridge case into the bore, also form part of said Browning patent and need therefore no further description here.

The hammer 38 fulcrumed at 85 in the trigger guard 33, is forced down and cocked by the rearward movement of the slide 43, which is facilitated by its slightly rounded front face as at 84. The cocking of the hammer takes place against the main spring 86 through the intermediary of the strut 87 which is hinged in the hammer 38 at 88, when finally the latter reaches its position shown in Figure 3, where the trigger 34 engages the hammer notch 37. As however the slide swings back the hammer slightly more than necessary for such engagement a small tooth 89 on the hammer engages under a sear notch 90 provided on the slide stop 41 which thus acts as a safety sear. This hammer mechanism is also similar to the said Browning mechanism, as already stated.

When the breech block and slide have been brought forward by the action of the loading handle through the rod 45 into firing position, the gun can then be fired in the usual manner by pulling the trigger.

I claim:—

1. In a firing mechanism for guns having a downwardly open receiver, the combination with a straight firing pin, a substantially solid breech block reciprocable in the receiver and provided in closed position with a longitudinal bore coaxial with the axis of the gun barrel and forming a fully dust proof housing for the firing pin in all positions, and means in said bore adapted to retract the point of the firing pin into the bore.

2. In a firing mechanism for guns having a receiver, the combination with a substantially solid breech block having an axial bore, a slide adapted to actuate said block and reciprocable in the receiver, a small recess being formed on the underside of the breech block, a short solid extractor having a short nose portion and a short tail portion and pivoted in said recess and substantially balanced therein, below said bore, and means for actuating the extractor to grip the rim

of the cartridge case, said means comprising a spring in said recess engaging said tail portion and a cam surface on the slide cooperating with said nose portion.

5 3. In a firing mechanism for guns having a receiver, the combination with a substantially solid breech block, a slide reciprocable in the receiver, and adapted to engage the breech block to partake in such reciprocation, 10 a small recess being formed on the underside of the breech block, a short solid extractor pivoted in said recess, and means for actuating the extractor to grip the rim of the cartridge case, a cam surface on the slide operating with said gripping means to firmly hold the extractor during retraction of said slide.

4. In a firing mechanism for guns having a receiver, the combination with a substantially 20 solid breech block, having an axial bore, a slide reciprocable in the receiver, and adapted to engage the breech block to partake in such reciprocation; a short extractor pivoted in the breech block below said bore, a cartridge 25 carrier pivoted in said receiver and actuated by the slide to raise a cartridge into loading position, shoulders on said carrier positioned in the path of an empty cartridge case extracted by said extractor, said extractor and abutments 30 cooperating to swing said cartridge case downwardly thereby ejecting the same through an opening in the bottom of said receiver, and means for actuating the extractor to grip the rim of the cartridge case.

35 5. In a firing mechanism for guns having a downwardly open receiver, the combination with a straight firing pin, a substantially solid breech block, a slide reciprocable in the receiver adapted to actuate the breech block, 40 said breech block being provided with a longitudinal bore forming a dust proof housing for the firing pin, means in said bore adapted to retract the point of the firing pin into the bore, a small recess being formed on the 45 underside of the breech block, a short solid extractor pivoted in said recess below said bore, and means on the slide for actuating the extractor to grip the rim of the cartridge case.

50 6. In a firing mechanism for guns having a receiver, the combination with a substantially solid breech block, a slide reciprocable in the receiver and adapted to engage the breech block to partake in such reciprocation, a firing pin, the breech block having a longitudinal bore forming a dust proof housing for the firing pin, the firing pin being adapted to deliver a blow in axial direction against the cartridge case cap; a recess being 55 formed in the underside of the breech block below said bore, a solid extractor pivoted in said recess and substantially balanced therein, means actuating the extractor to grip the rim of the cartridge case, a cam surface 60 on the slide cooperating with said gripping

means to firmly hold the extractor during retraction of the slide; a cartridge carrier pivoted in said receiver and actuated by the slide to raise a cartridge into loading position, shoulders on said carrier positioned in the path of an empty cartridge case extracted by said extractor, said extractor and abutments 70 cooperating to swing said cartridge case downwardly thereby ejecting the same through an opening in the bottom of said receiver.

In testimony whereof I affix my signature.
HARRY E. HOWLAND.
